UNITED STATES PATENT OFFICE.

ULYSSES G. McQUEEN, OF NEW ROCHELLE, NEW YORK.

SASH-PULLEY.

1,129,999.

Specification of Letters Patent. Patented Mar. 2, 1915.

Application filed May 21, 1913, Serial No. 769,115. Renewed January 21, 1915. Serial No. 3,634.

To all whom it may concern:

Be it known that I, ULYSSES G. McQUEEN, a citizen of the United States, and a resident of New Rochelle, county of Westchester, 5 State of New York, (whose post-office address is 3 West Twenty-ninth street, New York city,) have invented a new and useful Improvement in Sash-Pulleys, of which the following is a specification.

10 The object of my invention is to provide a pulley of the overhead class which will be cheap and durable in construction and fit in any suitable frame so as to be inconspicuous and firm in the position in which it is placed. 15 This, and other objects are accomplished by my invention, one embodiment of which is hereinafter set forth.

For a more particular description of my invention, reference is to be had to the accompanying drawings, forming a part hereof, in which—

Figure 1 is a sectional view of a part of a window frame with my improved pulley mounted therein. Fig. 2 is a cross-section of 25 my improved pulley when in place.

Throughout the various views of the drawings, similar reference characters designate similar parts.

My improved pulley 1 is provided with 30 a suitable casing 2 in which is mounted a spindle or bearing 3 which carries one or more pulleys 4 of the conventional kind. In the embodiment of my invention herein shown two such pulleys are employed so

that a sash may be balanced by a single 35 weight. The casing 2 has a suitable set of flanges 5 in the same plane as the bearing 3, which are adapted to rest on the upper surface of a frame 6, and it has a downwardly extending flange 7 that enters a corresponding opening or recess in this frame 6 immediately above the sash. This flange 7 extends to a lower level than the part of the casing 2 that is over a side 8 of the frame 6, so that the lower end of the flange 7 is held 45 between two surfaces and is hung from the flanges 5 whereby the casing 2 is held securely in place by the load it carries without the aid of a bolt, screws or other similar fixing means. 50

While I have shown and described one embodiment of my invention, it is obvious that it is not restricted thereto, but is sufficiently broad to cover all structures that come within the scope of the annexed claim. 55

What I claim is,

In a device of the class described, a casing having a bearing and laterally extending flanges in the plane of the bearing adapted to support the casing on top of a frame, and 60 a downwardly extending flange with parts adapted to extend between two surfaces of the frame, whereby the casing is kept from turning. 65

ULYSSES G. McQUEEN.
